GAS GUN

Anthony Theodore Escobar, San Quentin, Calif.

Application September 11, 1942, Serial No. 458,001

7 Claims.

(Cl. 42—51)

This invention relates to a gas gun in the form of a night stick or billy and has for its primary object the provision of a device of this character which will be extremely convenient to carry and use as a defense weapon, and which is capable of firing a plurality of gas shells, successively, and which may be easily and conveniently reloaded.

With these and other objects in view as will become more apparent as the description proceeds, the invention consists in certain novel features of construction, combination and arrangement of parts which will be hereinafter more fully described and claimed.

In the drawings:

Figure 1 is a side elevational view.

Figure 2 is a top plan view with parts broken away and shown in section.

Figure 3 is a rear elevational view.

Figure 4 is a front elevational view with the end cap removed.

Figure 5 is an enlarged fragmentary sectional view of the firing mechanism for sequentially firing the cartridges.

Figure 6 is a fragmentary longitudinal sectional view showing the rear end of the gun.

Figure 7 is a similar view of the front end.

Figure 8 is a similar view taken substantially on a line 8—8 of Figure 6.

Figures 9, 10 and 11 are transverse sectional views taken respectively on lines 9—9, 10—10 and 11—11 of Figure 6.

Figure 12 is a detail of the shaft locking device.

Figure 13 is a perspective view of the trigger actuated dog for the firing plungers.

Figure 14 is a fragmentary sectional view of the spring connected dogs forming part of the firing mechanism.

Figure 15 is a detail of the safety catch for the shaft, and

Figure 16 is a detail of the flexible locking finger for said safety catch.

Referring now to the drawings in detail, the numeral 5 designates a rigid tubular casing of a length to form a suitable night stick or billy and a portion at its rear end forms a hand grip equipped with a flared end cap 6 removably mounted thereon by set screws 7. The front end of the casing is reduced to receive a destructible end cap 8 held thereon by frictional fit.

Mounted in the front end of the casing is a barrel 9 provided with longitudinal grooves 11 and circumferential branch grooves 12, the grooves 11 slidably receiving lugs 13 formed on gas shells 14. The gas shells are arranged in end to end relation and are threadedly connected to

gether as shown at 14'. The innermost shell is provided in its inner end with a detonating cap 15 and the remaining shells are provided with detonating caps 16 and 17 in their side walls. The detonating caps communicate with powder chambers 18 in the rear ends of the respective shells. The powder chambers 18 occupy a comparatively small space within the shells, thus leaving the remaining portion of the shells for the storage of tear gas or similar chemical. Destructible partitions 19 are arranged between the gas chambers and the powder chambers of the shells and each shell has a substantially conical-shaped end partition or wall 20 of a rigid construction capable of withstanding the force of the exploding powder.

The barrel 9 is equipped with spring projected firing pins 21 and 21' in the walls of the barrel adapted for striking the detonating caps 16 and 17 and the inner end of the barrel is provided with a similar firing pin 22 adapted for striking the detonating cap 15.

The barrel 9 is formed with a thickened wall 23 in its upper portion provided with a longitudinally extending passage 24 within which is slidably mounted a pair of rods 25 and 26 in side by side relation as shown in Figure 2. The firing pins 21 and 21' project into the passage 24 in the path of the bevelled front ends of the rods 25 and 26 respectively, for riding over the pins to cause the latter to strike the detonating cap and fire the charge.

A sectional lever 27 composed of upper and lower overlapping sections 28 and 29 is pivoted at the rear end of the barrel, the lower section being engageable with the firing pin 22 and the upper section having a rearwardly projecting arm 30 terminating in the vertical plane of the rear end of the rods 25 and 26.

A shaft 31 is rotatably mounted transversely in the casing adjacent the rear end of the barrel and is provided with an upper spring retracted plunger 32 slidably mounted transversely in the shaft and a lower spring retracted plunger 33 similarly mounted in the shaft and angularly with respect to the axis of the upper plunger. The upper plunger is adapted to strike the rods 25 and 26 upon a predetermined rotary movement of the shaft and the lower plunger is likewise adapted to strike the arm 30 of the lever 27 for actuating the respective firing pins.

A ratchet 34 is secured to the shaft 31 with which a dog 35 is engageable, the dog being pivoted on a hammer in the form of a plate 50 by means of a pin 36. Also pivoted on the pin 36 is a second dog 38 extending in diverging relation

with respect to the dog 35 and yieldably connected to the dog 35 by means of a spring 39 coiled on the pin 36. A pin 40 projects laterally from the plate 50 at the crotch of oppositely extending dogs 35 and 38 to act as a stop in limiting the closing movement of the dogs.

A pin 41 also projects laterally from the dog 35 and is engaged by the notched end 42 of a rod 43 extending longitudinally in the casing and slidably mounted in guides 44. A coil spring 45 is mounted on the rod between the guides for projecting the rod rearwardly and outwardly of the cap 6 to form a handle 46 at the rear end of the rod.

A coil spring 47 engages the ratchet to urge the same in a direction to re-set the plungers 32 and 33 when the ratchet is released by the dog 35.

The plate 50 is pivoted on a pin 51 which is positioned transversely in the casing at right angles to the shaft 31, one edge of the plate being engageable with the rear ends of the plungers 32 and 33. A notch 52 is formed in the rear edge of the plate for receiving the free end of a leaf spring 53 secured in the casing by screws 54.

A trigger 55 is pivoted in the casing at 56 and projects through an opening 57 outwardly thereof. A lever 58 is pivoted intermediate its ends in the casing on a pin 59, the lower end of the lever being connected to the trigger by a link 60 through the medium of a pin 61 and slot 62, the upper end of the lever being adapted to engage the dog 38 for actuating the dogs and to rotate the plate 50 against the tension of the spring 53. A coil spring 63 is attached to the inner end of the trigger and is anchored to the pin 59.

The dog 35 is held in engagement with the ratchet by a leaf spring 64 attached to the plate 50 by means of a block 65 and to the block is also attached one end of safety catch 66 of spring metal having an upwardly extending hook 67 at its free end engaged over an upstanding arcuate lug or cam 68 projecting radially from the shaft 31 and a downwardly extending lug 69 also at the free end of the catch 66 adapted to enter a notch 70 formed in an adjacent edge of the dog 35 the angle of the notch enabling the catch 66 to hold the dog 35 out of engagement with the ratchet 34. The catch 66 is released from the dog 35 by the cam 68 upon a rotation of the shaft 31 during its resetting action by the spring 47.

A safety catch designated generally at 71 is provided and includes a spring finger 72, shown in detail in Figures 15 and 16, the finger being secured to one end of a pivoted cam 73 and the free end of the finger is selectively engaged in notches 74 in the peripheral edge of the ratchet 34. The arm 73 is pivoted on a pin 75 on which is also mounted a coil spring 76 urging the finger in engaged position and the other end of the arm projects upwardly into the path of the forward movement of the pin 41 for releasing the safety catch 71 upon an inward movement of the handle 46 and rod 43.

The finger 72 is secured against one side of the arm 73 so that the finger will flex when the ratchet is moved in a direction for the successive firing of the cartridge, but will not flex upon a tendency of the ratchet to move in an opposite direction and accordingly will lock the ratchet against such reverse movement and against the tension of spring 47.

The rear edge of the trigger 55 is formed with a notch 77 adapted for receiving the inner end of a locking rod 78 slidably mounted in the casing and

projecting rearwardly through the cap 6 to provide a handle 79.

A second coil spring 80 is secured to the trigger 55 and operates against the tension of the spring 63 to restrain actuation thereof, the spring 63 being stronger than the spring 80 to project the trigger from the opening 57 and the two springs cooperating to normally maintain the trigger and lever 58 in the position shown. In the operation of the device, and after the cartridges 14 have been loaded in the barrel, the trigger is held in a safety retracted position by the engagement of the end of the rod 78 in the notch 77 of the trigger, the trigger being released by a rearward movement of the handle 79 of the rod 78 to permit the spring 63 to project the trigger from the side of the handle 5, as shown in Figure 6.

The shaft 31 is normally held in position with the plungers 32 and 33 out of the path of the hammer 50 by the spring 47, as shown in Figure 8, and is locked in such position by the safety catch 71 engaging the notches 74 of the ratchet 34.

The dog 35 is held out of engagement with the ratchet 34 by the lug 69 engaged in the notch 70 of the dog.

When it is desired to fire the first cartridge the trigger is released by the handle 79 and the handle 46 is pushed inwardly to cause an engagement of the notched head 42 with the pin 41 which in turn engages the upper end 73 of the catch 71 to pivot the catch and retract the latter from the notches 74.

The rearward pulling force of the trigger 55 will move the upper end of the lever 58 into engagement with the lower end of the dog 38 which engages the pin 40 on the hammer 50 to rotate the hammer in a clockwise direction. The initial movement of the hammer will release the lug 69 from the dog 35 permitting engagement of the dog with the ratchet 34 to actuate the shaft 31 during the continued rotation or cocking of the hammer. This movement of the shaft will bring the plunger 32 into position for striking the rod 26.

After the hammer has been rotated a predetermined distance by the trigger, the lever 58 will ride past the dog 38 to release the hammer and the spring 53 which has been put under tension by the rotation of the hammer will rotate the hammer in an opposite direction to strike the plunger and fire the first cartridge.

Release of pressure on the trigger will return the lever 58 rearwardly past the dog 38 into the position shown in Figure 6, whereby the next rearward movement of the trigger will cause the dog 35 to move the ratchet 34 another notch and rotate the shaft 31 to bring the plunger 32 into position for striking the second rod 26 to fire the second cartridge.

The next firing movement of the trigger will move the plunger 33 into position for striking the firing lever 27 to fire the last cartridge.

While I have shown and described the preferred embodiment of my invention, it will be understood that minor changes in construction, combination and arrangement of parts may be made without departing from the spirit and scope of the invention as claimed.

Having described the invention what is claimed as new is:

1. In a device of the character described, a tubular casing having a hand grip portion at one end and a barrel at its opposite end, explosive gas shells in the barrel, one behind the other, a firing means in the casing behind the barrel for exploding said shells sequentially and including a plu-

rality of firing plungers, a rotatable support for the plungers, means for actuating the support in a step by step movement to successively bring the plungers into firing position, and trigger means for actuating the plungers to effect firing of the firing means.

2. In a device of the character described, a tubular casing having a hand grip portion at one end and a barrel at its opposite end, explosive gas shells in the barrel, one behind the other, a firing means in the casing behind the barrel for exploding said shells sequentially and including a plurality of firing plungers, a rotatable support for the plungers, ratchet means for actuating the support in a step by step movement to successively bring the plungers into firing position, and trigger means for actuating the plungers to effect firing of the firing means.

3. In a device of the character described, a tubular casing having a hand grip portion at one end and a barrel at its opposite end, explosive shells in the barrel, one behind the other, a firing means in the casing behind the barrel for exploding said shells sequentially and including a plurality of plungers and a pivoted hammer for striking the plungers, means carried by the hammer for successively moving the plungers into the path of the hammer, and a trigger for actuating the hammer.

4. In a device of the character described, a tubular casing having a hand grip portion at one end and a barrel at its opposite end, explosive shells in the barrel, one behind the other, a firing means in the casing behind the barrel for exploding said shells sequentially and including a plurality of firing plungers, a pivotally mounted hammer for striking the plungers, means carried by the hammer for successively moving the plungers into the path of the hammers, spring means for actuating the hammer, and a trigger for placing the hammer under the influence of said spring means.

5. In a device of the character described, a tubular casing having a hand grip portion at one end and a barrel at its opposite end, explosive shells in the barrel, one behind the other, a firing

means in the casing behind the barrel for exploding said shells sequentially and including a plurality of firing plungers, a rotatable mounting for the plungers, a pivotally mounted hammer for striking the plungers, means for moving the plunger mounting to bring the plungers into the path of the hammer, means carried by the hammer for securing the last-named means inactive, means for releasing said securing means by a predetermined movement of the mounting, and a trigger for actuating the hammer.

6. In a device of the character described, a tubular casing having a hand grip portion at one end and a barrel at its opposite end, explosive shells in the barrel, one behind the other, a firing means in the casing behind the barrel for exploding said shells sequentially and including a plurality of firing plungers, a rotatable mounting for the plungers, a pivotally mounted hammer for striking the plungers, means for moving the plunger mounting to bring the plungers into the path of the hammer and actuated by a predetermined movement of the hammer, means carried by the hammer for securing the last-named means inactive, means for releasing said securing means by a predetermined movement of the mounting, means for locking the mounting against movement, means for releasing the locking means and for actuating the mounting independently of the hammer, and a trigger for actuating the hammer.

7. A firearm comprising a tubular casing having a hand grip portion at one end and a barrel at its other end, explosive shells in the barrel, one behind the other, a firing pin at the rear of the barrel constructed and arranged for firing the rearmost shell and firing pins in the side of the barrel constructed and arranged for firing the remaining shells, and firing mechanism for sequentially actuating the firing pins and beginning with the firing pin for the outermost shells, said firing mechanism including sliding rods in the barrel constructed and arranged for successively engaging the firing pins in the side of the barrel.

ANTHONY THEODORE ESCOBAR.
